(57) **CLAIM**

The ornamental design for a firearm with deflector, as shown and described.

DESCRIPTION

FIG. 1 is a left side perspective view of a firearm with deflector in accordance with an embodiment of our design; FIG. 2 is a front elevational view of the firearm with deflector of FIG. 1;

FIG. 3 is a rear elevational view of the firearm with deflector of FIG. 1;

FIG. 4 is a left side elevational view of the firearm with deflector of FIG. 1;

FIG. 5 is a close-up, left side, top perspective view of the firearm with deflector of FIG. 1;

FIG. 6 is a close-up, left side, bottom perspective view of the firearm with deflector of FIG. 1;

FIG. 7 is a right side elevational view of the firearm with deflector of FIG. 1;

FIG. 8 is a top plan view of the firearm with deflector of FIG. 1; and,

FIG. 9 is a bottom plan view of the firearm with deflector of FIG. 1.

The broken lines having consistent dash lengths (dash-dash-dash) represent portions of the firearm that form no part of the claimed design.

The broken lines having inconsistent dash lengths (long dash-short dash-long dash) in FIGS. 1, 4-6, and 8 represent boundaries of the claimed design.

1 Claim, 8 Drawing Sheets
